UNITED STATES PATENT OFFICE.

ALBERT TURNER, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A CUT-GLASS VESSEL.

41,833.

Specification for Design.

Patented Oct. 10, 1911.

Application filed July 26, 1911. Serial No. 640,706. Term of patent 7 years.

To all whom it may concern:

Be it known that I, ALBERT TURNER, a citizen of the United States, residing at Meriden, in the county of New Haven and State of Connecticut, have invented a new, original, and ornamental Design for a Cut-Glass Vessel; and I do hereby declare the accompanying drawing to be a full, clear, and exact illustration of the same, and which said drawing constitutes part of this

specification, and represents a perspective view of a cut-glass vessel embodying my design.

I claim:

The ornamental design for a cut glass vessel as shown.

ALBERT TURNER.

Witnesses:

J. M. HARMON,
GEORGE D. BELKNAP.
